UNITED STATES PATENT OFFICE.

SAMUEL D. WEBB AND SULLIVAN C. SWETT, OF WASHINGTON, DISTRICT OF COLUMBIA, ASSIGNORS, BY DIRECT AND MESNE ASSIGNMENTS, TO SAID SWETT AND THOMAS A. MITCHELL, OF SAME PLACE.

PRINTER'S QUOIN.

SPECIFICATION forming part of Letters Patent No. 403,402, dated May 14, 1889.

Application filed May 15, 1888. Serial No. 273,973. (No model.)

To all whom it may concern:

Be it known that we, SAMUEL D. WEBB and SULLIVAN C. SWETT, citizens of the United States of America, residing at Washington, in the District of Columbia, have invented certain new and useful Improvements in Printers' Quoins, of which the following is a specification, reference being had therein to the accompanying drawings.

- 10 Our invention relates to quoins for locking up forms of type; and it consists in a quoins constructed in the form of a toothed cylinder provided at each end with a loosely-riveted roller of a diameter slightly larger than the 15 diameter of the cylinder, these quoins being used with short pieces of metal furniture straight on one side and inclined on the other side, the inclined side having a central toothed rib formed thereon.
- 20 Figure 1 of the accompanying drawings is a plan view of a form of type locked up by our improved quoins. Fig. 2 is a perspective view of one of the quoins. Fig. 3 is a vertical section of the quoin shown in Fig. 2. Fig. 25 4 is a perspective view of the metal furniture. Fig. 5 is an elevation of the key used for locking up and unlocking the form.

In order to enable others skilled in the art to make and use our invention, we will proceed to describe it with reference to the drawings.

A represents our improved quoins, which consists of a cylinder, *a*, toothed longitudinally, as seen in Figs. 2 and 3, and two rollers, *a'*—one at each end of the cylinder. These rollers are loosely secured on the cylinder, preferably in the following manner: The cylinder is shouldered circumferentially, as at 1, and the rollers are beveled off on one inner edge, as at 2. Then, when the rollers are placed over the ends of the cylinder until they rest against the shoulders, the ends of the cylinder are riveted down, as at 3. By this means the rollers are held in place on the cylinder, 45 and yet are free to revolve thereon.

As will be seen in Figs. 2 and 3, the cylinder is of less diameter than the rollers, and is formed with a square hole centrally through

it for the reception of the key *K*, by which the quoins is operated to lock and unlock the 50 form.

Our quoins may be cast or otherwise formed of brass or other suitable metal.

B represents a piece of metal furniture straight on one side and inclined on the other. 55 On the inclined side there is formed a raised toothed rib, *b*, which extends centrally the entire length of the furniture. We prefer to make the furniture of wrought-iron and in lengths of from three to five inches, in which 60 case it is necessary to use only one quoins with each piece; but it is evident that the side and foot sticks may each be formed with a series of ribbed and toothed inclines, in which case, as in the case of the short lengths of furniture, there will be but one quoins for each incline.

C represents reglets placed between the form and furniture to fill out, as will be readily understood.

K represents the key, the squared lower end, *k*, of which is adapted to fit the opening in the quoins, the handle being formed at one end with a screw-driver, *k'*, and at the other end with a hammer, *k''*.

In locking up a form the chase *D* is put on, and then reglets or other straight pieces of furniture are placed next the type to fill out until the quoins, when in place, will bear against the chase. The inclined furniture 80 and the quoins are then set, after which the latter are turned by the key *K* in the direction of the arrow, which causes the teeth on the furniture, whereby the quoins are carried up 85 the incline with a wedging action. It will be noticed, however, that as the rollers of the quoins are slightly larger than the cylinder they alone bear against the chase, allowing the cylinder to turn freely, and that as the diameter 90 of the rollers is not sufficiently greater than that of the cylinder to permit them to roll on the plane surfaces of the furniture there can be no tendency to disengage the cylinder from the toothed rib. It results from this 95 construction that as the quoins is operated

to lock the form the cylinder will be rolled up the toothed incline while the loosely-attached rollers will be drawn up.

Having thus described our invention, what we claim as new, and desire to secure by Letters Patent, is—

The combination, with a piece of furniture straight on one side and having an inclined toothed rib on the opposite side, of a quoin consisting of a toothed cylinder having an opening for the reception of a key and two rollers of slightly greater diameter than the

cylinder, one of said rollers being loosely attached to each end of the cylinder, substantially as described, and for the purposes set forth.

In testimony whereof we affix our signatures in presence of two witnesses.

SAMUEL D. WEBB.
SULLIVAN C. SWETT.
